US00D774093S

(12) **United States Design Patent** (10) **Patent No.:** **US D774,093 S**
Dye et al. (45) **Date of Patent:** **** Dec. 13, 2016**

(54) **DISPLAY SCREEN OR PORTION THEREOF WITH ICON**

(71) Applicant: **Apple Inc.**, Cupertino, CA (US)

(72) Inventors: **Alan C. Dye**, San Francisco, CA (US);
Jonathan P. Ive, San Francisco, CA (US); **Joe Marianek**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/540,350**

(22) Filed: **Sep. 23, 2015**

Related U.S. Application Data

(63) Continuation of application No. 29/523,717, filed on Apr. 13, 2015, now Pat. No. Des. 740,322, which is a continuation of application No. 29/457,311, filed on Jun. 9, 2013, now Pat. No. Des. 726,765.

(57) **CLAIM**

The ornamental design for a display screen or portion thereof with icon, as shown and described.

DESCRIPTION

The FIGURE is a front view of a display screen or portion thereof with icon showing the claimed design.

The outermost broken lines in the FIGURE show a boundary of a display screen or portion thereof, and form no part of the claimed design. The other broken lines in the FIGURE show portions of the icon that form no part of the claimed design.
